UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

TRAIN-DOOR CONTROL SYSTEM.

Application filed August 11, 1920. Serial No. 402,894.

To all whom it may concern:

Be it known that I, LEE P. HYNES, a citizen of the United States, residing at Albany, in the county of Albany and State of New York, have invented certain new and useful Improvements in Train-Door Control Systems, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 is a diagram of my system; Figs. 2 and 3 show switch details, and Figs. 4 and 5 show modifications.

Fig. 6 is a detail view illustrating the key switch.

My invention relates to a system of train-door operation, and includes means for subdividing a train line into sections in such a way that an operator on one car can work as one operating unit the doors on his own car and also those on one or more cars either ahead of him or behind him. I also arrange that a single set of door circuits on the operating car can be transferred from a train-line section ahead of to a corresponding section behind the operator's station. By this means the duplication of such door sets and the resulting complications are avoided and the addition of train-line operation to single-car operation is independent of the normal set of circuits used with a single car. I also combine the aforesaid device with my system, heretofore devised, for utilizing a single wire to both open and close a plurality of doors along a car or train instead of using two wires, one for the opening, the other for the closing operation.

Referring to the drawing A¹ and A² represent two adjacent sections of train-wire which will be connected in the usual way, by jumpers, from car to car throughout the train. These sections A¹ and A² will normally stand connected by contact plate *a* of a drum switch that is shown more in detail in Fig. 3, and will serve for all the doors on one side of the car, or the plurality of cars that may be included in one operating unit. A duplicate series of sections will be employed for doors on the opposite

side. Since the said sections A¹ A² are normally connected by the plate *a*, no shifting of the drum switch will be required on any cars of the train except those on which an operator is located, nor will it be required if the cars are operated singly, the train-line jumpers being then omitted. For convenience the car where an operator is stationed will be designated as a "sending" car, the others, composing an operating unit, being "receiving" cars. In a sending car the operator on entering the car will turn the drum switch either to left or right, according as the unit which he is to operate is ahead of him in the train or behind him. By this means the train can be made up prior to and regardless of its subsequent division into units for door operation. Only when the operator enters a car to take his station will he create a section point in the train line by turning the drum switch. Obviously it is not necessary to decide, until the train is about to start, whether one man will control the doors on two cars, or three cars or more and the decision involves only the choice of one particular car as his station. Since the traffic conditions would naturally determine whether it was advisable for one man to take charge of the doors on a greater or less number of cars, it is highly desirable that the sectioning of the train line for larger or smaller units should be thus simply and easily provided for. Moreover it allows the units to be of different lengths. In a ten-car train for instance the two units near the center of the train, where it is liable to be crowded, may be each composed of two cars, with a three-car unit at each end of the train. Or if there is an odd number of cars in the train, either end section can include the odd car. This flexibility of my system is therefore of much practical value. If the drum switch is turned to the right it disconnects wire A¹ from plate *a*, creating a break in the continuity of the train-line at that point, but the wire A² will remain in contact with the plate *a*. The third, intermediate contact bearing on plate *a* is connected to the wire 8 leading to the local door-operating apparatus and is at all times in contact with the plate. Hence the said wire 8 and the apparatus to which it leads is shifted to connection with wire A¹ or wire A² according to the direction in which the drum

switch is turned. If it connects with A^2 , the switch being turned to the right, then the operator, by means of his local apparatus and circuits, to be hereinafter described, will have control of the doors on all the cars to the right of him up to the next operator's station where the train-line is again broken at the plate a . In addition he will also control the doors on his own car. If he should turn his drum switch to the left, he would similarly have control of all the doors to the left of him as far as the next operator's station on that side and the break there in the continuity of the train-line. It will also be observed that this result is facilitated by the fact that the train-line consists of only one wire. The operator will preferably be stationed at the rear end of the unit which he is operating so that he will control the doors between his station and the next operating station towards the forward or leading end of the train. That arrangement will bring the last operator on the rear of the train where he is needed as a lookout and flagman. If he should go out to flag a train approaching from behind, the next man ahead of him can take temporary charge of the flagman's doors by shifting his own switch a to the rear. If the train reverses its direction, as it might do at the end of its route, the flagman will merely go back to the car at the opposite end of the train, the other operators remaining in the same positions, but using the train-line on the other side of the cars.

Referring to the local circuits on the car, the two switch contacts represented at d and f are in the nature of the usual preparatory "key switches" which the operator must manipulate before he presses his door-closing or door-opening button. These are usually locked so that he must use a key to unlock them before he can move them and render his push buttons operative. This prevents the use of the buttons by unauthorized persons. I have added to this switch a push-button interlock which will be described later. The switch d is the customary one for connecting to the battery so that the apparatus will have current. The battery wire is marked with the "plus" sign both at this point and elsewhere in the drawing, it being understood that in practice a single battery will be used and a wire therefrom brought to each of the points thus marked. The switch d normally stands open as shown in Fig. 1. The switch f normally stands closed, thereby completing the circuit of wire 5 which serves, when the car is a "receiving" car to transmit the current from the train-wire, via wire 8, to the relay K via wire 7. When the car is a "sending," instead of a "receiving" car, the wire 5 must be open. Therefore when the op-

erator uses his key he closes switch d and opens switch f . The switches b^1 , b^2 are on the drum switch that operates contact a and one of said switches is closed irrespective of whether the drum is turned to right or to left to make the car a "sending" car in the way I have described. The closing of either switch b^1 — b^2 closes the circuit of the wire 6 which serves to transmit battery current to the train-line whenever the train door-opening button O^1 is pressed. The local door-opening button O^2 is only for the one car and, when pressed, causes the battery current to flow by wire 7 to the relay K which produces the opening of the doors on the particular car where the operator is stationed. At all of the "receiving" cars however the current which goes to wire 7 and relay K comes from the train-line by wire 5 and closed switch f as I have described having been first delivered to the train wire by the pressing of train button O^1 on the sending car of the unit. In either case the relay K becomes energized and its armature, which normally connects the battery to contact points c^1 , c^2 , c^3 , is lifted and then it connects the battery to the contact points o^1 , o^2 , o^3 , which are connected respectively to the door-opening valve-magnet O at each of the several three doors 1, 2 and 3. I have shown in full the circuits at only one of these doors, viz: door 3, these circuits being duplicated at the other doors 1 and 2. These door circuits are shown diagrammatically since they are, in substance, the well known circuits of McElroy Patent No. 1,287,717 of December 19, 1918. They are here shown for two doors which move together to close and draw apart to open, and are provided on the front end with the usual fender shoes x^1 and x^2 which, in the event of a door meeting an obstruction in closing, yield inwardly and close an electric contact at D . Each shoe is connected to a contact W mounted on the moving door and each contact D is connected to a similarly mounted contact S . W and S move respectively in contact with stationary strips G and F (although W is out of contact with G when the door is closed, as shown in the drawing). When the door is open W passes off from G and bridges two short stationary strips T and R . From the aforesaid contact point o^3 controlled by relay K a wire 3 leads to the door-opening valve magnet O , with a branch to each of the strips F . From the opposite contact point c^3 wire 4 leads to the door-closing valve-magnet C via contact strips T and R when T and R are bridged. The two sides of contacts T and R are in parallel branches of wire 4. Obviously this route by wire 4 is only completed when the doors are open and at least one set of the short strips T and R bridged by contact W , but it is only

when the door is open that there is any occasion to energize the said door-closing valve-magnet C. As is customary, the momentary energizing of magnet O or magnet 5 C will start the door on its opening or its closing run which run will continue till the door automatically shifts its own valve at the end of its run and stops.

Assuming the doors to be closed, the lifting 10 of the armature of relay K (following the pressing of button O² on a "sending" car, or the inflow of current to K via the train-wire and wires 5 and 7 on a "receiving" car) will send battery current via point o³ 15 and wire 3 to magnet O and the door will open, bridging T and R when fully open. Then, to close the doors again it will be necessary for the operator to press the button C¹, for the doors on the "receiving" cars, and 20 then the button C² for the doors on his own "sending" car. These two buttons C¹ and C² merely act to release the corresponding buttons O¹ and O² which had been previously pressed to open the doors and when so 25 pressed had remained in their depressed position. Thus, referring to Fig. 2, the depression of button O¹ closes the circuit at contacts x and y and the contact lever is then locked in its depressed position by the 30 latch z. Then the subsequent depression of button C¹ merely throws back the latch z and allows button O¹ to rise and break the circuit which it had been holding closed at the points x and y. So long as button O¹ 35 remains depressed current is maintained on the relay K and the valve-magnets O but if desired, the door may itself act, when wholly or partly opened, to break the connection between wire 3 and valve magnet 40 O. Thus, as shown in Fig. 4, the magnet O may be connected to a supplementary strip F¹ covered by contact S', and so receiving current from wire 3 until the door is open or partly open, when the contact S' 45 passes off it and leaves O with no current. Thus O merely remains energized until the doors reach their open position. Since the doors are ordinarily open for short periods only, it is not important to cut off the current 50 from the magnets O during these periods but it may be done in the way I have described, if so desired. Upon the aforesaid unlatching of the opening buttons and the consequent dropping of the armature 55 of relay K to its normal position, battery current will then flow to point c³, and, since strips T and R are now bridged by the open door-contact W, it will flow from point c³ to wire 4 and thence via T, W and R to door-closing valve-magnet C. That will 60 initiate the closing movement of the door, but the aforesaid circuit to magnet C will be broken as soon as contact W passes off strips T and R, so that no current will remain on that magnet during the long period

when the doors are closed, while, of course, there is no current in the relays K during that period. If either one of the two doors, which we assume are now in the act of closing, should encounter an obstruction, the 70 corresponding door-shoe will yield and close on its contact D. That will obviously establish an emergency circuit from battery to strip G and thence via W, D and S to strip F and door-opening valve-magnet O. Thereupon 75 the door will instantly reverse from its closing to its opening movement, and will run back till contact W leaves strip G and bridges T and R, thereby deenergizing O and energizing C. Then the door will again 80 reverse to its closing direction and will complete its closing run if the obstruction has been removed. If it has not been removed, the fender shoe will again be moved to close the circuit at D and the described operations will be repeated until the obstruction is no longer present when the closing run will be completed.

Referring to Fig. 6, which illustrates the key switch mentioned above, P represents a switch disc of insulation on which is mounted a contact-plate p that normally closes the aforesaid switch f, but when turned 90 degrees to the right opens f and closes d as heretofore described. This disc 90 is rotated by means of a key inserted in key-hole q, the key being trapped in the disc by means of the face-plate (not shown) except when the keyhole in the plate registers with keyhole q in the disc. Such a key-switch 95 is well known, but I have added to the disc a lug H which, each time that the switch is turned, engages an extension on the upper side of a cross bar J and depresses it. The ends of bar J are loosely engaged by the 100 stems of the door-closing switch-button C¹ and C² and rest on pins projecting from the stems. Each time that the drum switch is turned the depression of bar J also depresses the buttons, so that, if the door-opening buttons O¹ and O² should happen 105 to be down and latched they would be unlatched as I have described in connection with Fig. 2. The purpose of this arrangement is to insure that the door-opening buttons are not held down and therefore in position to close the circuit of relay K, when the switch d closes to admit current to the system. This insurance is effected because 110 the act of turning the key-switch either to or from its key-releasing position positively pushes down the door-closing buttons which unlatch the door-opening buttons. This precaution is desirable, because the door-opening buttons might be pushed in, while the train is running, inadvertently or 115 maliciously, but ineffective at the time to cause the opening of the doors because of the absence of current on the system. Then the turning of the key-switch preparatory 120

to door operation would admit current and the doors would open while the train was still running. That accident is avoided by the device just described.

5 The system herein disclosed, by which a single train-wire is employed for both the opening and the closing of doors on the same side of the car, is also shown and claimed in its broader aspect in my application Serial 10 No. 374,323 filed April 16, 1920. So far as it may be involved in the claims of the present case it is only in association with features not contained in said prior application, and as a specific matter, since my 15 present invention is not limited to a train line of that type.

What I claim as new and desire to secure by Letters Patent is:

1. In a train door-operating system a sectional train-line, a door-operating circuit on each car, and a switch on each car having contacts connected to each of two adjacent sections of the train-line and also to said door-operating circuit whereby said circuit 25 may be connected to either one of the two sections.

2. In a train door-operating system, a sectional train-line, local operating circuits for a group of two or more doors on each car, 30 and a switch for shifting said circuits to either one of two adjacent sections of the train-line.

3. In a train door-operating system a sectional train-line, a local circuit on each car 35 containing a relay, two or more door-operating circuits controlled by said relay and a switch for shifting said relay circuit to either one of two adjacent sections of train-line.

40 4. In a train door-operating system, a train-line divided into sections, a local door-operating circuit on each car, a switch contact connected to said circuit and cooperating contacts connected to each of two adjacent 45 train-line sections, and means for moving the switch forward or rearward to connect the said circuit to the forward or rearward train-line sections respectively.

5. In a train door-operating system, a sectional train-line, local door-operating circuits on each car, means for connecting each of said circuits to either one or two adjacent train-line sections, a relay in each local circuit, and means for connecting said relay to the train-line or to a local battery. 55

6. In a train door-operating system, a sectional train-line, switches normally connecting the sections to form a continuous train-line but movable to interrupt the 60 train-line at any car, a local door-operating circuit on each car containing two branches one branch leading to a relay and the other

to a switch connected with a source of current and means for connecting each local circuit to the train-line on either side of the 65 point of interruption thereof when the interruption occurs.

7. In a train door-operating system, a sectional train-line, a local door-operating circuit on each car, independent of the train 70 line, a door-opening magnet responsive to the closing of said door-operating circuit, and a door-closing magnet responding to the opening of said door-operating circuit.

8. In a train operating circuit a single 75 train line divided into sections, means normally connecting the train line sections but movable to interrupt the train line on any car, a local door opening magnet, a local door closing magnet, and control means for 80 said magnets normally connected to the continuous train line.

9. In a train door-operating system, a sectional train-line, switches on each of the several cars normally connecting the train-line sections, a local door-operating circuit containing a relay, a switch normally connecting said local door-operating circuit to the train-line, means on each car for interrupting the train-line at a point on any car 90 and disconnecting the local door-operating circuit on the same car from the train-line, a door-opening magnet responding to the flow from the train-line to said local circuit, and a door-closing magnet responding to the 95 cessation of such current-flow.

10. In a train door-operating system, a sectional train-line normally continuous, a local door-operating circuit on each car containing a relay and normally connected to the continuous train-line, a local circuit connected with a source of current, means for interrupting the train-line on any car, a switch on the same car for connecting the interrupted train-line to the said source of current, and door-opening and door-closing magnets both controlled by the same one of the relays aforesaid. 100

11. In a train door-operating system a sectional train-line, switches on the several cars normally connecting the train-line sections but movable to interrupt the train-line on any car, a local circuit on each car normally connected to the continuous train-line, a relay in each local circuit, door-opening and door-closing magnets controlled by the same relay, means for connecting a source of current to the train-line for operating the door-opening magnets and for disconnecting it from the train-line to operate the door-closing magnets. 110

Signed at Albany, N. Y., August 4th, 1920.

LEE P. HYNES.
